United States Patent Office

Des. 216,707
Patented Mar. 3, 1970

216,707

FURNITURE PANEL OR THE LIKE

Richard M. Chapin, Charlotte, N.C., assignor to Dolly Madison Industries, Louisville, Ky., a corporation

Filed Jan. 6, 1969, Ser. No. 15,210

Term of patent 3½ years

Int. Cl. D6—01
U.S. Cl. D33—1

The back of the furniture panel shown is substantially plain and unornamented.

I claim:

The ornamental design for a furniture panel or the like, substantially as shown and described.
